DOUBLE-HEADED BOWLING PIN

Carl C. Jennings, 3107 Graciosa Lane,
Anaheim, Calif. 92804

Filed June 14, 1974, Ser. No. 479,623

Term of patent 14 years

Int. Cl. D21—01

U.S. Cl. D34—5 GP

FIG. 1

FIG. 2

FIG. 3

FIG. 4

FIG. 5

FIG. 1 is a front-elevational view of my new ornamental design for a double-headed bowling pin;
FIG. 2 is a rear-elevational view thereof;
FIG. 3 is a side view of the present invention;
FIG. 4 is a top plan view thereof; and
FIG. 5 is a bottom plan view thereof.

I claim:

The ornamental design for double-headed bowling pin,
as shown and described.
